UNITED STATES PATENT OFFICE

151,912

DESIGN FOR A COMBINED CIGARETTE CASE AND LIGHTER

James P. Partlow, Youngstown, Ohio

Application February 12, 1946, Serial No. 126,508

Term of patent 7 years

(Cl. D48—27)

To all whom it may concern:

Be it known that I, James P. Partlow, a citizen of the United States, residing at Youngstown, in the county of Mahoning and State of Ohio, have invented a new, original, and ornamental Design for a Combined Cigarette Case and Lighter, of which the following is a specification, reference being had to the accompanying drawing, forming a part thereof.

The back of the combined cigarette case and lighter is substantially plain.

I claim:

The ornamental design for a combined cigarette case and lighter, as shown and described.

JAMES P. PARTLOW.
